PUNCHING MACHINE

Edward J. Rabenda, Binghamton, N. Y., assignor
to International Business Machines Corporation,
New York, N. Y., a corporation of New
York

Application December 31, 1937, Serial No. 182,748

19 Claims. (Cl. 164—115)

This invention relates to punching machines and more particularly to the type which is adapted to punch holes at predetermined points of an accounting machine control card.

5 Punching machines of this type are widely in use and comprise several forms and are adapted to punch control cards to represent data, the punching mechanism thereof being controlled by various controlling instrumentalities such as keys, other punched or master cards, settable devices of the manually settable type, or of the type set under control of accounting elements of accounting machines, etc.

10 Such forms of punching machines have been found to be extremely accurate in their operation even when operated at high speeds. However, such machines, like other machines, are despite the high quality of manufacture and proper design, susceptible to wear and tear, and sometimes 15 are operated under disadvantageous conditions, such as in places where dust and dirt may enter within the machine. Under such conditions the machine may fail to punch properly and to guard against such rare instances the present machine includes an arrangement to detect such conditions 20 and effectively warn the operator. This warning is an indication of the requirement for service, cleaning or adjustment of parts. This warning is given at the first instance of improper punching thereby preventing the machine from running continuously and improperly punching a large 25 batch of cards and unknowingly permit their subsequent use with resultant errors in accounting operations performed under control of these cards.

30 It is, therefore, the main object of the present invention to provide for a punching machine a means for detecting whether cards are punched to represent the desired data to be punched under control of certain controlling means.

35 More specifically, it is an object of the present invention to provide means to cause the actuation of a punch pin and means controlled by the punch pin for indicating that the punch pin has not been actuated by the actuating means.

40 A still further object of the invention is to provide means for effecting certain distinctive markings on a punched card if the card is not properly punched to represent the desired data.

45 A still further object of the present invention is to provide means for causing the punching mechanism to go through a second cycle of operation in the event that the first cycle of operation has caused the improper representation of data by the failure to punch a card, but to prevent 50 further operation of the punching mechanism, i. e., the third cycle of operation.

The present invention is illustrated in connection with a punching machine of a well known type and to illustrate the invention it is presumed 55 that a card or cards are to be punched to repre-

sent data set up in a controlling device. Such controlling device may be set to represent a total under control of an accumulator of an accounting machine, another punched card, but for simplicity is shown in connection with a simple form 5 of commutators manually set to represent data to be punched.

In the present machine for the purpose of illustration the machine goes through a card feeding cycle so as to feed the card step-by-step past a 10 line of punch pins, and magnets are energized under control of the commutators to select the punch pins for actuation.

For each punch pin there is provided a relay 15 magnet in a normally open circuit having two sets of contacts in the circuit, one set of contacts being closed in accordance with the energization of the punch control magnet and the other set of contacts being closed by and when the punch pin is actuated. The simultaneous closure of both sets 20 of contacts retains the circuit open, but if one set opens at a dissimultaneous time the relay magnet is energized. This will cause the punching machine to stop and the relay magnet will cause a light to be illuminated and the marking 25 of the card to indicate an error in punching.

The machine preferably includes means to cause the punching machine to go through another cycle of operation, but if the next cycle of operation should also effect an omission of the 30 punching then the machine will actually stop in its operation.

The present invention is shown for purposes of illustration in connection with a punching machine of a well known type shown and described in the patent to C. D. Lake, #2,032,805, dated March 35 3, 1936 but may be utilized in connection with other punching or marking machines as well.

Further objects of the instant invention reside in any novel feature of construction or operation or novel combination of parts present in the 40 embodiment of the invention described and shown in the accompanying drawings whether within or without the scope of the appended claims and irrespective of other specific statements as to the scope of the invention contained herein.

45 In said drawings:

Fig. 1 is an outside view of the punching machine showing in detail the driving mechanism therefor.

Fig. 2 is a view of a portion of a punched card showing a cancellation notch at the bottom indicating an omitted punching operation.

Fig. 3 is a detail view of the punching mechanism and the electrical punch selecting devices 55 therefor.

Fig. 4 is a detail view of the Geneva drive for the card feeding mechanism.

Fig. 5 is a timing diagram of cams and other devices controlling electrical contacts.

Fig. 6 is a longitudinal sectional view of the punching machine.

Fig. 7 is an electrical wiring diagram.

Fig. 8 discloses a modified form of a contact 5 operating device shown for only one order.

When the current supply is applied to the line wires 10, 11 (Fig. 7) the motor M is started in operation and runs continually as long as the line switch S is closed.

10 The blank cards 12 to be punched are placed in a supply magazine 13 (Fig. 6) so that the lowermost card rocks a pivoted card lever 14 to close card lever contacts MCL.

15 From Fig. 1 it is evident that motor M drives a pulley 15 to which pulley 15 there is secured a pinion 16 driving a gear 17 to which there is secured a pinion 18 meshing with a gear 19 which is loosely mounted on a shaft 20.

20 Attached to gear 19 is a notched disk 22 loose on the shaft 20. Adjacent the disk 22 is an arm 23 secured to the shaft 20 and carrying a clutch pawl 24 pivoted thereon. The pawl has an extension adapted to fit in the notch 22a of the 25 disk 22 and is urged to engage the disk by a spring 25. However the pawl is held disengaged by an armature latch 26 which engages an extending arm of the pawl. When the card feed clutch magnet 27 is energized the associated 30 armature is attracted and latch 26 is rocked to the left about pivot 28, releasing pawl 24 for actuation by spring 25 and connecting shaft 20 to the driving gears.

A gear 21, attached to the shaft 20 is in mesh 35 with a gear 29 which is in mesh with a gear 29' secured to a shaft 30'.

The shaft 30' carries a series of cams adapted to close contacts herein designated as CC contacts, one of such, for instance, being the contacts CC-1 shown in Fig. 6. The timing of these and other cam contacts is shown in Fig. 5. Therefore, as will be seen in Fig. 7 a relay magnet 32 is energized when a start key "Start" is depressed. The latter closes its relay contacts 32a 40 to provide a stick circuit under control of contacts CC-1. Magnet 32 closes its contacts 32b (top of sheet) to energize the card feed clutch magnet 27. The circuit extends from line side 10, magnet 27, relay contacts 32b, cam contacts 50 CC-2 now closed, to line side 11.

When shaft 20 is rotated a pair of complementary cams 33, 34 (Fig. 4) are operated. A two-armed lever 35 secured to a shaft 36 carries a pair of rollers cooperating with the cams 33, 34 so as to rock the shaft 36. Attached to the rock shaft 36 are sector arms 37 (Fig. 6) provided with gear teeth that mesh with racks on the picker slides 38. A picker 39 attached to the slides is adapted to engage the bottom card in the hopper 13 and move the card to the left (Fig. 6) when the picker slides 38 are reciprocated by the cams 33, 34 on the shaft 20.

The first cycle of machine operation in which a card is fed from the supply magazine 13 brings 65 the leading edge of the card to a line of punches 40 while the second cycle of machine operation feeds the card past the punches and by feeding rollers to be later described the punched card is ultimately fed to a storage hopper 41.

70 When cards are in the magazine a lever 14 is rocked as previously stated to close contacts MCL to thereby cause a relay magnet 43 to be energized to retain its relay contacts 43a closed as long as there are cards in the supply magazine.

75 When cam contacts CC-1 open, the motor

relay magnet 32 would be deenergized, causing the opening of relay contacts 32b and the consequent deenergization of the card feed clutch magnet 27 and card feeding would thereupon stop but to cause the automatic operation of the card feeding mechanism the following is provided. During the first card feeding cycle the first card will cause the closure of die card lever contacts DCL so that when cam contacts CC-3 close at the end of the first cycle and before cam contacts CC-1 open to deenergize magnet 32 a circuit will be closed from line side 10, to a relay magnet 44, cam contacts CC-3, card lever contacts DCL to line side 11, thus energizing relay magnet 44. The latter closes its stick contacts 15 44a and also relay contacts 44b. The stick circuit for relay magnet 32 is now through relay contacts 32a, relay contacts 135b normally closed, relay contacts 44b, relay contacts 43a now closed, through stop key "Stop" to the line side 11. By 20 the last described circuit the relay contacts 32b will be retained closed so that each time the cam contacts CC-2 close an impulse will be transmitted to the card feed clutch magnet 27 for each of the successive card feed cycles, and as 25 long as cards are being fed, unless card feeding is interrupted in a manner to be subsequently described.

The gear 16 (Fig. 1) is attached to the pulley 15 and both are attached to a shaft 47 (Fig. 4) 30 which rotates continually. A roller 48 (Fig. 4) on a stud extending from the gear 16 forms a means for driving a Geneva step motion gear 49 with an intermittent movement. The Geneva gear 49 is attached to a shaft 50 but is locked in 35 each position by the cooperation of a concentric formation 51 at the end of each radial extension with a hub 52 on shaft 47. The roller 48 moves idly for the greater part of the arc about shaft 47 until it engages in one of the slots 53 in gear 49. The gear is moved with a gradually accelerated and then gradually retarded motion which is stopped as the roller 48 slips out of a slot 53. The gear 49 is released for each step of movement by a depression 54 in the side of hub 45 52. The depression 54 is presented only when the roller 48 is in position to drive the gear 49.

Attached to the shaft 50 is a gear 55 (Fig. 4) which meshes with a gear 56 and a gear 57. The gear 57 is attached to a shaft 58 to which is secured a pinion 59 (Fig. 1) in mesh with a pinion 60 attached to a shaft 61. As shown in Fig. 6 a pair of rollers 62 is secured to the shafts 58 and 61 and thereby the card is fed between and by the rollers 62 and to the series of punches 40 in 55 a step-by-step motion. To feed the card as it passes the series of punches there is provided a pair of rollers 63 (Fig. 6) attached to shafts 64. Shafts 64 are intergeared by pinions 65 (Fig. 1) and the uppermost pinion 65 is rotatable with 60 the gear 56.

Therefore, the card is fed by the pairs of rollers 62 and 63 in a step-by-step movement past the line of punches 40 of which there is one for each column of the card.

Referring to Fig. 6 and the wiring diagram disclosed in Fig. 7, when the card to be punched emerges from the supply magazine 13, it operates a card lever to cause the closure of the die card lever contacts DCL causing when cam contacts CC-3 close, as previously stated, the energization of the relay magnet 44 and the closure of its relay contacts 44c thereby extending the line side 11 to a commutator ring 66 of an emitter shown in Fig. 1 and designated emitter Em. As shown 75

in Fig. 1, the gear 38 meshes with an idler pinion 67 which is in mesh with a gear 68 attached to the shaft 69 of the emitter Em. The gear 68 is driven by the gear 38 through an idler pinion 67. A brush 70 engages the segment 66 and the brush 71 engages one of a series of segments 72. Through the gear driving connections shown the segments 72 are successively engaged by the brush 71 in the order that the corresponding index points of the card to be punched are presented to the punches 40 (Fig. 6) of the punching machine.

Amount setting devices

For the purpose of illustrating the present invention, there is disclosed a plurality of manually settable devices which are settable to predetermine the amounts or numbers to be punched upon the successive cards. Such amount number controlling mechanism is best shown in Fig. 6 wherein it will be noted that each order of number setting device comprises a manually settable wheel 73 attached to which is a brush carrying element adapted to carry electrically connected brushes 75 (see Fig. 7) which are positioned manually by the setting of the wheel 73 so that one brush coats with an electrically conducting segment 76 and the other brush with a selected one of a series of segments 77. The particular segment 77 which is engaged by the brush read-out device is dependent upon the number to be punched in the corresponding card column.

A plurality of such settable read-out devices is provided wherein it will be noted that the segments 77 representing the same digit in each of the brush read-out devices are connected together by a wire 78, the plurality of wiring connections 78 being connected to the corresponding segments 72 of the emitter Em. If, for example, the brush structure 75 should be positioned to represent "9" as shown by dotted lines in Fig. 7 then the card will be perforated at the nine index point position to represent "9" by the following electrical connections. At the time the "9" index point position is beneath the punch 40 brush 71 engages the "9" segment 72, extending the circuit through a wire 78 connected to the "9" segment 72, to the segment 77, (Fig. 7) which is engaged by the related brush structure 75 and by its commutator segment 76, the line is extended to a plug socket 79. By a plug connection 80 to a socket 82 the circuit extends to a punch control magnet 81 which is connected to the other line side 10. While only several punch control magnets 81 are shown the machine is preferably provided with a series of punch control magnets 81, one for each card column, and the plug connections 80 are made from the sockets 79 to the sockets 82, which are connected to the punch magnets 81, in order that the card may be punched at the predetermined columns. Only one emitter is necessary for a series of the manually settable devices which are to control punching operations. Thus, as the card is stepped along it is punched in the various columns.

Any suitable punching mechanism may be provided and the following is a description of the preferred form which is shown in detail in the patent issued to C. D. Lake, No. 2,032,805 dated March 3, 1936.

After leaving the first set of rollers 62, the card is fed between a stripper plate 83 and a die plate 84. Then the card enters between the

pair of feed rollers 63 which feed it to the storage hopper 41.

The selective operation of the punch plungers 40 will be described with reference to Figs. 3 and 6. In Fig. 3, it will be noted that the continually rotating shaft 47 is formed with an eccentric 85 which is encircled by an arm 86. The upper end of this arm is pivotally connected to an arm 87 on shaft 88 which is provided with another pair of arms 89. Between these arms 89 and a punch 10 operating ball 90, there is provided an adjustable turn-buckle connection. A threaded rod 91 is pivoted at 92 on arm 89 and another rod 93 is pivoted at 94 on ball 90, both rods being connected by a left and right threaded bolt 95 which is adjustable to vary the position of the ball 90.

Ball 90 is pivoted on a stud 96 in the main side frames and carries a punch actuating bar 97 which is adapted to cooperate with notches 98 (Fig. 3) in any of a plurality of selected interposer pawls 99. Each of the punch plungers 40 has an interposer pawl 99 which is pivotally connected thereto by a pin 100. Normally, the pawl 99 is held out of the path of the bar 97 and the plunger 40 is held above the die plate 84 by a spring 101 attached to the pawl. However, when the punch control magnet 81 is energized, the associated pawl is drawn into cooperation with the bar 97 and the related plunger is subsequently depressed to perforate the card. The armature 102 of the punch controlling magnet 81 is part of a lever 103 pivotally connected at 104. The lower end of lever 103 is pivotally connected to a call wire 105, the other end of which is pivoted at 106 to pawl 99. A plurality of such connections are made, one to each pawl, the magnets 81 being arranged in staggered rows of columns. The brackets 107 carry the magnets of one row as a unit and have arms 108 which hold an insulation bar 109 suspended upon the magnets to function as a terminal bar. When attracted, the armature 102 swings the lever 103 in a clockwise direction (Fig. 3) and draws wire 105 to the left, urging pawl 99 into cooperation with bar 97. The wires 105 are guided by a slotted plate 110 and the pawls 98 are aligned by slots in a plate 111 fastened on a supporting bar 112, the plate 111 also being used to secure one end of springs 101. The edge of bar 112 cooperates with a cam face 113 on each of the pawls 99 to more positively hold the selected pawls in cooperation with the bar 97 as the bar 97 is lowered. An extension 114 on a fixed bar 115 cooperates with the upper ends of the pawls to cam them in a clockwise direction out of engagement with the ascending bar 97 on the return stroke of the ball. In order to positively hold the pawls in disengaged position the end of the bar 97 cooperates with a cam face 116 on each pawl. There is a limit to the downward motion of the punch plungers 40 because of the presence of a fixed bar 117 which projects into notches 118 cut in the side of punch plungers 40. The punch plungers are guided above the holes in die plate 84 by sliding in holes of the fixed bar 119 and the stripper plate 83.

The operation of the punching is timed to occur during the pause in card feeding when the Geneva wheel 49 (Fig. 4) is not in action. The eccentric 85 is placed on the shaft 47 in such a position that when the ball 90 is reciprocated the roller 48 is out of engagement with the wheel 49. As the ball 90 and bar 97 are reciprocated, any of the pawls may be moved.

over by the call wires until notches 88 engage the end of bar 97. Then the connected pawls and plungers are depressed to perforate the card and quickly withdraw therefrom to permit the feeding of the card to the extent of another hole step to thereby position the next index point positions of a horizontal line of the card to the line of punch plungers 40.

Checking feature

10 It is desirable to determine whether the punch plunger 40 has been actually depressed as a result of the electrical impulse transmitted to the related punch controlling magnet 81.

15 This checking device is shown, by way of example, for the controlling devices for two card columns, and obviously will be provided for as many column checking devices as there are columns being punched.

20 For each controlling magnet 81 there is provided a relay magnet 120 which is in parallel with the punch control magnet 81, as seen in Fig. 7. Each magnet 120 when energized opens its contacts 120a and closes contacts 120b. Referring to Fig. 3 it will be seen that slidably mounted in the stripper plate 83 is a plunger 121 and it will also be noted that the punch plunger is provided with a cut or cam-shaped depression 122. A pivoted double arm 123 has its lower arm abutting one end of the plunger 121 and the other arm is pivoted at 124 to a rod 125 having a hook portion 126 hooking over the center blade of contacts 127 and 128. The resiliency of the center blade rocks the double-arm 35 123 through the rod 125 so that the lower arm of the double arm abuts the plunger 121. When the punch plunger 40 is depressed the cut or cam-shaped depression 122 thereof receives the plunger 121 to permit the resiliency of the center 40 blade of contacts 127 and 128 to open the former and close the latter, as is evident from Fig. 3.

Referring to Fig. 7 it is evident that wires 129 and 130 interconnect the contacts 120a, 120b, 127 and 128 in such manner that between line wires 131 and 132 there is normally an open circuit. However, if the punch plunger 40 should not be depressed when magnet 120 is energized relay contacts 120b will be closed and contacts 127 will remain closed thus connecting line wires 131 and 132. The result would be the same if the punch plunger 40 was depressed and the magnet 120 not energized, in which case contacts 128 would close to connect line wires 131 and 132. Cam contacts CC-4 connect the line 55 side 11 with the wire 131 during the time the magnets 120 are energized during the punching operations.

The wire 132 is connected to one side of the three pick-up relay magnets designated by numerals 133, 134 and 135, the other side of these magnets being connected to the line side 10, and all are energized when line wires 131 and 132 are interconnected.

The pick-up relay magnet 133 will close its 65 relay contacts 133a to cause the holding magnet 137 to be energized since cam contacts CC-5 now closed are in circuit connection with the relay contacts 133a. The holding magnet 137 will also by its energization cause contacts 133a to be held closed and as long as cam contacts CC-5 are closed.

The relay magnet 134 will close its relay contacts 134a thereby energizing a holding magnet 136 which causes it to retain contacts 134a closed. 70 In multiple with the magnet 136 is a signal

lamp 147. Obviously, the illumination of this lamp is an indication of an error in punching or a failure to properly punch and the lamp is retained illuminated until a key 138a is depressed to open the circuit by disconnecting the line 5 side 11.

The energization of the pick-up magnet 135 will cause the closure of relay contacts 135a which will cause a relay magnet 138 to be energized, the circuit being from line side 10, relay magnet 138, relay contacts 135a, cam contacts CC-6 to the line side 11. When cam contacts CC-7 close at the "13th" point in the cycle a circuit will be made from line side 11, cam contacts CC-6 closed at this point in the cycle, relay contacts 135a, cam contacts CC-7, relay magnet 139, to the line side 10. The relay magnet 139 causes the closure of its relay contacts 139a, thereby extending a circuit from the line side 10, a punch control magnet 81, a socket 82, plug connection 142, a socket 143 to relay contacts 139a, the contact point 7213, brushes 70, 71, commutator segment 66, relay contacts 44c, to the line side 11. The punch magnet 81 is selected to punch a special notch 150 (see Fig. 2) in a desired column and is effected by a related punch plunger 40 when the bottom of the card is correlated with the punch plunger, at which time cam contacts CC-7 close to energize relay magnet 139 and the segment 7213 is contacted to cause the selected punch control magnet 81 to be energized. The reason that the error designation appears as a notch is that at the time the punch control magnet 81 is energized to effect this punching operation the leading edge of the card 35 is substantially mid-way of the line of punches 40. Of course, if the card was slightly longer, designation 150 would not appear as a notch but as a hole, like the holes shown in the card of Fig. 2. By timing the energization of the magnet 81 so as to be energized slightly earlier, an error designating perforation can be provided. However, the notch is more suitable and more easily identified as to its meaning, since if it was a hole it might be interpreted as the perforation 40 representing "9".

It will be recalled that the relay magnet 32 is retained energized through the relay contacts 135b, and obviously with the disagreement effected the contacts 135b will open to cause the cessation of the card feeding and punching cycle. This may be desirable in some cases but in others it may be desirable to effect a repetition punching and by means now to be described this is preferably effected.

It will be seen that relay contacts 32a and relay contacts 135b are shunted by relay contacts 133b and relay contacts 143b so that even though relay contacts 135b open as a result of a disagreement the relay contacts 133b closing as 60 a result of the disagreement together with relay contacts 143b shunt the relay contacts 135b. As a result of this shunt circuit the relay magnet 32 will be retained energized so that the punching machine will go through a second 65 cycle of machine operation even though the preceding punching operation has been in error.

As a result the second card punching cycle ensues and from Figs. 5 and 7 it will be seen that at the initial part of the cycle cam contacts 70 CC-8 close. It will be recalled that the relay contacts 133a are held closed by the energization of the holding relay magnet 137 and the latter is retained energized during the second card punching cycle by the closure of cam con- 75

5 contacts CC-5. Hence when cam contacts CC-8 close a pick-up relay magnet 144 will be energized, the circuit being from line side 10, relay magnet 144, cam contacts CC-8, relay contacts 133a, 10 cam contacts CC-5 to line side 11. Relay magnet 144 will cause the closure of its relay contacts 144a to cause the energization of the holding relay magnet 143 the circuit being from line side 10, magnet 143, relay contacts 144a closed by relay magnet 144, cam contacts CC-8 to the line side 11. The magnet 143 will also keep contacts 144a closed and such will remain closed during the remainder of the cycle, due to the continued closure of cam contacts CC-8.

15 If a disagreement should be effected during the second cycle of operation relay magnet 135 will be energized, as before, to open contacts 135b and relay magnet 133 will be energized to close its relay contacts 133b as before, but since relay contacts 143b are now open the shunt circuit for relay contacts 135b comprising relay contacts 133b and relay contacts 143b is open so that the relay magnet 32 is deenergized and the third punching cycle will not be effected.

20 25 The operator will notice the stopping of the machine and observing that cards are still in the magazine and noticing the illumination of the lamp 147 it will indicate to him that two cards bearing cancellation notches 150 have been improperly punched and the reason for this can be investigated.

25 30 If so desired the relay magnet 120 may be dispensed with and the relay contacts 120a and 120b can be controlled by the punch control magnet 81 itself, as shown in Fig. 8 thus eliminating a number of parts and simplifying machine. It is the intention, therefore, not to limit the claims to the particular form of control including the specially provided relay magnet 120.

35 40 While there has been shown and described and pointed out the fundamental novel features of the invention as applied to a single modification it will be understood that various omissions and substitutions and changes in the form and details of the device illustrated and in its operation may be made by those skilled in the art without departing from the spirit of the invention. It is the intention, therefore, to be limited only as indicated by the scope of the following 45 claims.

50 What is claimed is:

1. In a punching machine, in combination, card punching means, actuating means therefor, means for selecting said punches for operation by said actuating means, means for detecting the failure of operation of any selected punch by said actuating means, and means for effecting under control of said detecting means the distinctive characterization of a card which is erroneously punched.

55 60 65 70 75 2. In a cyclically operable punching machine, punches and actuating means therefor, means for initiating and means for effecting continued successive cyclic operations of said punches and said actuating means, means for detecting the failure of any punch to be actuated by said actuating means, and means for causing said detecting means to control the operation of the means for effecting the continued cyclic operation of the punches and said actuating means.

3. In a cyclically operable record punching machine, including punches and actuating means therefor, means for initiating and means for effecting continued cyclic operation of said punches and said actuating means to punch suc-

cessive records, devices for inhibiting the operation of the means for effecting continued cyclic operations of said punches and actuating means, detecting means for detecting the failure of a punch to be actuated by said actuating means, and means for causing said detecting means to control the operation of said devices.

4. In a cyclically operable punching machine, means for causing the successive automatic cyclic operations of said machine, a punching mechanism comprising punch instrumentalities and means for selecting said instrumentalities for operation, detecting means controlled by said punch instrumentalities and said selecting means for detecting the actual operation of the former under control of the latter, and means for causing said detecting means to control the operation of said first-named means in accordance with the results determined by said detecting means.

5. In a cyclically operable punching means, punches and actuating means therefor, means for initiating and means for effecting continued cyclic operations of said punches and said actuating means, means for detecting the failure of any punch to be actuated during each cyclic operation, devices for rendering the means for effecting continued cyclic operations ineffective, and means under control of said detecting means and responsive to the operation of the detecting means in detecting the failure of a punch to be actuated by said actuating means during two cyclic operations for causing said devices to be effective.

6. In a cyclically operable punching machine, punches and an actuating member therefor, means for effecting continued cyclic operation of said punches and said actuating member, means for detecting the failure of any punch to be actuated in each cyclic punching operation, devices controlled by said detecting means to prevent said first-named means from being effective to cause continued cyclic operations, other means rendered operative under control of said detecting means during the failure of any punch to be actuated in the same cyclic operation to render said devices ineffective whereby a successive cyclic operation will follow, and means under control of said detecting means and responsive to the operation of the detecting means in detecting the failure of a punch to be actuated during the second or successive cyclic operation for causing the first-named means to be ineffective to thereby prevent continued cyclic operations.

7. In a punching machine, a single line of punches, actuating means therefor, a plurality of means for causing the actuation of said punches by said actuating means to punch a record at predetermined index points thereof, devices for controlling the operation of the machine, means for detecting the failure of a punch to be actuated by said actuating means, and means for causing the detecting means to control the operation of said devices.

8. In a punching machine, punching mechanism therefor including punches and actuating means therefor, data representing means, means under control thereof for causing the selective operation of said punches by said actuating means, a machine control device for said punching machine, means controlled by the last-named means and said punches for detecting whether said punch pins are operated by said actuating means for effecting the punching of data repre-

- sented by said data representing means, and means for causing said detecting means to control the operation of said machine control device.
9. In a punching machine, devices for stopping the operation of the machine, a plurality of punches, actuating means therefor, means for selecting said punches for actuation by said actuating means conjointly controlled by said punches and said selecting means for detecting the failure of the operation of a punch by said actuating means in response to said selecting means, and means for causing said detecting means to control the operation of said devices.
10. In a punching machine, punches, punch actuating means, means for causing the selection of said punches for actuation by said actuating means, means for controlling the operation of the machine, means controlled conjointly by said punches and said selecting means for determining whether all of the selected punches have been actuated by said actuating means, and means for causing the last-named means to control the operation of the means for controlling the operation of the machine.
11. In a punching machine, a punching mechanism including punches and actuating means therefor, means for selecting said punches for operation by said actuating means, a checking means for determining whether selected punches are actuated by said actuating means comprising devices operated under control of said punches and other devices operated under control of said selecting means, and control means responsive to the operation of both of the aforesaid devices.
12. In a punching machine, punches, punch actuating means, selecting means for causing the actuation of said punches by said actuating means, devices operated by the actuation of said punches, other devices operated under control of the selecting means for causing the actuation of said punches, and testing means for determining whether said devices have been simultaneously operated.
13. In a punching machine, a punch, actuating means therefor, a punch control magnet for causing by an electrical impulse transmitted to said magnet the actuation of said punch by said actuating means, a checking circuit including a relay magnet in said circuit, contacts operated by the actuation of said punch, other contacts operated by a magnet receiving the electrical impulse transmitted to the punch control magnet, and means for causing both of said contacts to control said checking circuit for controlling the energization of the relay magnet in accordance with the simultaneous or dissimultaneous operation of both of said contacts.
14. In a cyclically operable record punching machine, punches and actuating means therefor, cyclically operable means for feeding successive records to said punches, detecting means operative in each successive punching operation of the machine; for detecting the failure of a punch to be actuated by said actuating means, and means for causing said detecting means to control the operation of said record feeding means to cause record feeding operations to be terminated subsequent to the operation of the machine in which failure of punching occurs.
15. In a cyclically operable punching machine, punches, actuating means for operating said punches, record feeding means for feeding records to said punches, power operated means for causing the operation of said actuating means and said record feeding means, means for detecting in each successive punching operation of the machine the failure of the operation of a punch by said actuating means, and means for causing said detecting means to control the operation of the power operated means to cause the cessation of operation of the record feeding means in a machine operation subsequent to the operation of the machine in which failure of punching occurs.
16. In a record punching machine, a punching mechanism including punches and actuating means therefor, a start key, record feeding means for feeding records to the punches, means under control of the start key for initiating the operation of the feeding means, means for effecting continued cyclic operation of the record feeding means, means for detecting the failure of an operation of a punch by said actuating means, and means for causing said detecting means to control the operation of the means for effecting continued cyclic operations of the record feeding means.
17. In a cyclically operable record punching machine, punches and actuating means therefor, cyclically operable means for feeding successive records to said punches, detecting means for detecting the failure of a punch to be actuated by said actuating means, and means controlled by said detecting means and responsive to the detecting means detecting the second failure of a punch to be actuated by said actuating means to render said feeding means inoperative.
18. In a punching machine, punches, means for feeding records to be punched in a step by step operation past said punches, means for effecting continued cyclic operation of said feeding means for successively feeding records to said punches, means for successively actuating said punches in an operation synchronous with said step by step feeding operation, detecting means for detecting the failure of a punch to operate to punch the record, and means for causing said detecting means to control the operation of the means for effecting the continued cyclic operation of said feeding means.
19. In a record punching machine, a punching mechanism including punches and actuating means therefor, a start key, record feeding means for feeding records to the punches, means under control of the start key for initiating the operation of the feeding means, means for effecting continued cyclic operation of the record feeding means, means for detecting the failure of an operation of a punch by said actuating means, devices controlled by said detecting means to control the operation of the means for effecting continued cyclic operations of the record feeding means for causing said means to be ineffective upon the failure of a punch to be actuated in each cyclic operation, other means controlled by the detecting means for effecting the second cyclic operation of the feeding means upon the first failure of a punch to be actuated irrespective of the operation of said devices, means set up during the second cycle of operation, and means operated under control of the set-up means and the aforesaid devices controlled by the detecting means when the latter detects the second failure of a punch to be actuated for causing the record feeding means to stop in its operation.

EDWARD J. RABENDA.
